US00D481898S

(12) **United States Design Patent** (10) Patent No.: **US D481,898 S**
Mendis (45) Date of Patent: **** Nov. 11, 2003**

- (54) **FLOCKED RUBBER MAT DESIGN "A"**
- (75) Inventor: **Hilarian Chrishan Salinda Mendis, Ratmalana (LK)**
- (73) Assignee: **Rileys Limited, Colombo (LK)**
- (**) Term: **14 Years**
- (21) Appl. No.: **29/136,263**
- (22) Filed: **Jan. 26, 2001**
- (51) LOC (7) Cl. **06-11**
- (52) U.S. Cl. **D6/583; D6/585**
- (58) Field of Search **D6/582-594; D32/47, D32/55, 57; D5/47, 49, 50, 53, 56, 59, 63, 99; 15/215-217, 161; 4/581-583; 428/80, 82, 83, 85, 86, 89-92, 95; 5/417, 420; 52/177-181**
